Assistant Examiner — Elizabeth Anne Glassberg

(57) **CLAIM**

The ornamental design for a set of cat climbing boxes as shown and described.

DESCRIPTION

1. Set of cat climbing boxes

1.1 : Perspective view shown in assembled position

1.2 : Perspective view shown in assembled position

1.3 : Exploded

1.4 : Perspective view of the first box

1.5 : Perspective view of the first box

1.6 : Front view of the first box

1.7 : Back view of the first box

1.8 : Left view of the first box

1.9 : Right view of the first box

1.10 : Top view of the first box

1.11 : Bottom view of the first box

1.12 : Perspective view of the second box

1.13 : Perspective view of the second box

1.14 : Front view of the second box

1.15 : Top view of the second box

1.16 : Bottom view of the second box

1.17 : Perspective view of the third box

1.18 : Perspective view of the third box

1.19 : Front view of the third box

1.20 : Back view of the third box

1.21 : Left view of the third box

1.22 : Right view of the third box

1.23 : Top view of the third box

1.24 : Bottom view of the third box

1.25 : Perspective view of the fourth box

1.26 : Perspective view of the fourth box

1.27 : Front view of the fourth box

1.28 : Back view of the fourth box

(Continued)

- 1.29** : Left view of the fourth box
1.30 : Right view of the fourth box
1.31 : Top view of the fourth box
1.32 : Bottom view of the fourth box
1.33 : Perspective view of the fifth box
1.34 : Perspective view of the fifth box
1.35 : Front view of the fifth box
1.36 : Back view of the fifth box
1.37 : Left view of the fifth box
1.38 : Right view of the fifth box
1.39 : Top view of the fifth box
1.40 : Bottom view of the fifth box
1.41 : Perspective view of the sixth box
1.42 : Perspective view of the sixth box
1.43 : Front view of the sixth box
1.44 : Back view of the sixth box
1.45 : Left view of the sixth box
1.46 : Right view of the sixth box
1.47 : Top view of the sixth box
1.48 : Bottom view of the sixth box

The broken lines in the reproductions depict portions of the set of cat climbing boxes that form no part of the claimed design; the back, left and right views of the second box are omitted because they are the same as the front view.

1 Claim, 48 Drawing Sheets
